ALARM CLOCK

Max Schlenker, La Salle, Ill.

Application August 1, 1936, Serial No. 93,795

6 Claims. (Cl. 58—16)

My invention relates generally to electrically operated alarm clocks, and more particularly to an improved indicator means with mechanism for setting and operating the alarm mechanism in this type of clock as well as in the regular spring driven type of clocks.

It has for its object the production of such an alarm indicating means in which each of the indicating parts therein associated is easily and readily distinguished in and by itself but more especially more visible, distinct and easily read when the parts are assembled and associated with each other. In addition to being thus more easily read the parts are extremely simple, inexpensive to produce and readily and easily assembled. When assembled the combined parts constitute an indicating means that is capable of very close adjustment and of very great accuracy in setting the time when the alarm shall sound.

I accomplish these objects by the means shown in the accompanying drawings in which:

Fig. 1 is a rear view of the clock movement.

Fig. 2 is a right side view of the same, the bell and its bracket being omitted.

Fig. 3 is a partial rear view of said movement showing the alarm mechanism.

Fig. 4 is a partial right side view of the same.

Fig. 5 is a sectional view of the alarm setting 30 and tripping mechanism.

Fig. 6 is an axial view of the same.

Similar numerals represent the same parts throughout the several views.

In the drawings 1 represents the front frame plate and 2 the rear frame plate of the clock. Said frame plates 1 and 2 are mounted on and held in proper position by the pillars 3 and the pillar nuts 4.

Adjacent to, and on the inner side of said frame plate 1, are attached the stator plates 5 and 6 of the synchronous motor shown that drives the hands of the clock, and on the inner side of said stator plates 5 and 6, are attached the auxiliary stator plates 7 and 8.

45 Journally mounted in frame plates 1 and 2 is the rotor shaft 9, to which is fixed the rotor 10 and the rotor pinion 11. Said rotor pinion 11 engages gear wheel 12 which is rotatably mounted on the center shaft 13, journally mounted in frame plates 1 and 2. Integral with said gear wheel 12 is the pinion 14 which engages intermediate gear wheel 15 rotatably mounted on a pin 16, which is fastened in frame plate 1. Integral with gear wheel 15 is the pinion 17 which 55 engages intermediate gear wheel 18 rotatably

mounted on said center shaft 13. Integral with gear wheel 18 is the pinion 19 which engages intermediate gear wheel 20 rotatably mounted on said pin 16. Integral with said gear wheel 20 is the pinion 21 which engages gear wheel 22, frictionally mounted on said center shaft 13. The rotation of rotor 10 is transmitted to said center shaft 13 in conventional manner, by the train of gears and pinions above described. Shaft 13 is also manually rotated by means of the knob 10 shown thereon to set the hands of the clock and the disc 37 is also rotated thereby at the same time.

Fixed to said center shaft 13 is the pinion 23 which meshes with the gear wheel 24 rotatably mounted on stud 25 which is fastened in frame plate 1. Integral with said gear wheel 24 is the pinion 26 which engages the gear wheel 27 fixed to the shaft 28 which is journally mounted in frame plates 1 and 2 and has its left end part 20 threaded. On said shaft 28 is rotatably mounted the sleeve 29 to which is affixed the trip cam 30 having lobe 31. Attached to the forward end of said sleeve 29 (see Fig. 5) is the gear wheel 32, on the front face of which is marked the alarm 25 indicator arrow 33 (see Fig. 6).

Said sleeve 29, which has fastened thereto the trip cam 30 and gear wheel 32, is frictionally rotatable on shaft 28, said friction being supplied by the coiled spring 33 abutting the stop 30 collar 34 which is mounted on shaft 28, as shown.

Fastened to the forward end of shaft 28 by means of the threads 34a thereon and the nut 35, is the hub 36 through the means of its internal threads as shown. On said hub 36 is fixed 35 the transparent disc 37. On the side of said disc 37 adjacent to the gear wheel 32 is marked the usual alarm dial divisions and numbers, as shown. Friction washer 38 is mounted between gear wheel 32 and the hub 36 so that gear wheel 32 can be 40 manually rotated in relation to disc 37. This transparent disc 37 can be shaped like a lens so that it will magnify or enlarge the divisions and numbers on the side thereof as well as the alarm indicator arrow on gear wheel 32 above mentioned. 45

Journally mounted in frame plate 2 as shown, 50 is the shaft 39, to which is fixed the set pinion 40 and the thumb knob 41. Said set pinion 40 engages the gear wheel 32.

Journally mounted in frame plates 1 and 2 is the shaft 43, to which is fixed the thumb knob 55

- 44 and the usual gear segment 45, the teeth of which are bent at a slight slant so that they will readily engage the rotor pinion 11 and start the rotor rotating by means of the spring 45a which is tensioned thereby in the usual manner.
- 5 5. Mounted on the sides of the stator plates 5 and 7, on the one side, and plates 6 and 8, on the other side, are the pole pieces 46, 47 and 48, about which is wound the conventional coil 49.
- 10 10. Said pole pieces 46, 47 and 48 are fastened to said stator plates, on each side, by the bolts 50 and the nuts 51, as shown.
- At the extremity of pole piece 46 is the projection 52. At the extremity of pole piece 48 is the projection 53, to which is fixed the studs 54. The flexible member 55 is held adjacent to said projection 53 by the coiled springs 56 mounted on said studs 54 as shown.
- 15 15. Fastened to said flexible member 55 by means of two rivets 57 is the armature 58, so disposed as to be in the magnetic field of said projection 52 of the pole piece 46. At the extremity of member 55 is fastened the hammer 59.
- 20 20. Mounted adjacent to frame plate 2 by means of nut 60 and screw 61 is the bracket 62 which carries the bell 63, as shown.
- 25 25. Journally mounted in frame plates 1 and 2 is the shaft 64, to which is fastened the lever 65 having the projections 66, 67, 68 and 69. Said projection 66 is so disposed as to bear on the periphery of trip cam 30 under pressure of the flat spring 70 acting on projection 67.
- 30 30. Mounted on frame plate 2, by means of the rivet 71 is the lever member 72 having the projections 73, 74 and 75. The projection 73 serves as a handle for the manual operation of said lever 72, while the projection 74 which contacts the corner of the plate, as shown, serves as a stop to limit the motion of said lever 72. The projection 75 engages projection 68 of lever 65 to bring projection 69 into engagement with armature 58, as shown, to lock the hammer 59 to keep it from striking the bell 63 and thus stop the further ringing of the alarm.
- 35 35. When it is desired to set the alarm mechanism of my clock the operator rotates the gear wheel 32 by means of the knurled knob 41 which rotates the pinion 40 meshing with said gear 32 until the indicator on said gear lines up with the proper division on the transparent member 37 which sets the cam 30 in proper position so that the alarm mechanism will operate to sound at the time indicated.
- 40 40. From the above description it is evident that my alarm setting means is very simple in operation, very inexpensive to produce and the numbers and divisions thereon readily and easily seen so that it is capable of very close adjustment with practically no effort on the part of the operator.
- 45 45. It will be understood, of course, that while I have here shown one form of my invention, I do not wish to limit it to the exact form shown, but desire to have it taken in a sense illustrative of all or any of the forms that come fairly within the scope of the appended claims.
- I claim:
1. In an alarm clock, a clock movement frame
- with time keeping means mounted therein including an alarm mechanism, a shaft journaled in said frame rotated by said time keeping means, a cam and gear wheel connected with each other and frictionally mounted on said shaft, an indicating means on said gear wheel, means for manually rotating said gear wheel, a transparent disc having a plurality of co-operative divisions and consecutive numbers thereon fastened on said shaft adjacent to said gear wheel, and alarm releasing means associated with said cam.
2. In an alarm clock, a clock movement frame with time keeping means mounted therein including an alarm mechanism, a shaft journaled in said frame rotated by said time keeping means, a cam and gear wheel connected with each other and frictionally mounted on said shaft, an indicating means on said gear wheel, means for manually rotating said gear wheel, a transparent disc having a plurality of divisions and consecutive numbers thereon co-operating with said indicating means and adjustably fastened on said shaft adjacent to said gear wheel, and alarm releasing means associated with said cam.
- 15 3. In an alarm clock, a clock movement frame with time keeping means mounted therein including an alarm mechanism, a shaft journaled in said frame rotated by said time keeping means, a sleeve frictionally mounted on said shaft, a cam and a gear wheel fastened on said sleeve, an indicating means on said gear wheel, means for manually rotating said gear wheel, a transparent disc having a plurality of co-operative divisions and consecutive numbers thereon fastened on said shaft adjacent to said gear wheel, and alarm releasing means associated with said cam.
- 20 4. In an alarm clock setting means including a time keeping means mounted in a movement frame, a shaft journaled in said frame rotated by said time keeping means, a cam and gear wheel fastened together frictionally mounted on said shaft, an indicating mark on said gear wheel, a transparent disc having a plurality of divisions with consecutive numbers co-operating with said mark fastened on said shaft adjacent to said gear wheel and manual means for rotating said gear wheel.
- 25 5. In an alarm setting means, an alarm mechanism including a shaft rotated in timed relation, a gear wheel and a cam fastened together and frictionally mounted on said shaft, an indicating means on said gear wheel, a transparent disc having a plurality of co-operative indicating divisions and numbers thereon fastened on said shaft adjacent to said gear wheel and means for manually rotating said gear wheel.
- 30 6. In an alarm setting means, an alarm mechanism including a shaft rotated in timed relation, a gear wheel and a cam fastened together and frictionally mounted on said shaft, an indicating means on said gear wheel, a transparent magnifying means having a plurality of co-operative indicating divisions and numbers thereon fastened on said shaft adjacent to said gear wheel and means for manually rotating said gear wheel.
- 35 7. In an alarm setting means, an alarm mechanism including a shaft rotated in timed relation, a gear wheel and a cam fastened together and frictionally mounted on said shaft, an indicating means on said gear wheel, a transparent disc having a plurality of co-operative divisions and numbers thereon fastened on said shaft adjacent to said gear wheel, and alarm releasing means associated with said cam.
- 40 8. In an alarm setting means, an alarm mechanism including a shaft rotated in timed relation, a gear wheel and a cam fastened together and frictionally mounted on said shaft, an indicating means on said gear wheel, a transparent disc having a plurality of divisions and consecutive numbers thereon co-operating with said indicating means and adjustably fastened on said shaft adjacent to said gear wheel, and alarm releasing means associated with said cam.
- 45 9. In an alarm setting means, an alarm mechanism including a shaft rotated in timed relation, a gear wheel and a cam fastened together and frictionally mounted on said shaft, an indicating means on said gear wheel, a transparent disc having a plurality of divisions and consecutive numbers thereon co-operating with said indicating means and adjustably fastened on said shaft adjacent to said gear wheel, and alarm releasing means associated with said cam.
- 50 10. In an alarm setting means, an alarm mechanism including a shaft rotated in timed relation, a gear wheel and a cam fastened together and frictionally mounted on said shaft, an indicating means on said gear wheel, a transparent disc having a plurality of divisions and consecutive numbers thereon co-operating with said indicating means and adjustably fastened on said shaft adjacent to said gear wheel, and alarm releasing means associated with said cam.
- 55 11. In an alarm setting means, an alarm mechanism including a shaft rotated in timed relation, a gear wheel and a cam fastened together and frictionally mounted on said shaft, an indicating means on said gear wheel, a transparent disc having a plurality of divisions and consecutive numbers thereon co-operating with said indicating means and adjustably fastened on said shaft adjacent to said gear wheel, and alarm releasing means associated with said cam.
- 60 12. In an alarm setting means, an alarm mechanism including a shaft rotated in timed relation, a gear wheel and a cam fastened together and frictionally mounted on said shaft, an indicating means on said gear wheel, a transparent disc having a plurality of divisions and consecutive numbers thereon co-operating with said indicating means and adjustably fastened on said shaft adjacent to said gear wheel, and alarm releasing means associated with said cam.
- 65 13. In an alarm setting means, an alarm mechanism including a shaft rotated in timed relation, a gear wheel and a cam fastened together and frictionally mounted on said shaft, an indicating means on said gear wheel, a transparent disc having a plurality of divisions and consecutive numbers thereon co-operating with said indicating means and adjustably fastened on said shaft adjacent to said gear wheel, and alarm releasing means associated with said cam.

MAX SCHLENKER.
